UNITED STATES PATENT OFFICE.

THOMAS H. CARROLL, OF PHILADELPHIA, PENNSYLVANIA, ASSIGNOR TO
THE CARROLL CHAINLESS CYCLE COMPANY, OF NEW JERSEY.

DESIGN FOR A BICYCLE-FRAME.

SPECIFICATION forming part of Design No. 26,953, dated April 20, 1897.

Application filed March 10, 1897. Serial No. 626,887. Term of patent 14 years.

To all whom it may concern:

Be it known that I, THOMAS H. CARROLL, of the city and county of Philadelphia, State of Pennsylvania, have invented a Design for 5 Bicycle-Frames, of which the following is a specification.

My design is illustrated in the accompanying drawing, which shows a perspective view of a bicycle-frame embodying my design.

- 10 A is the usual center stay of the frame.
- B is the crank-bracket.
- C C are the back stays.
- E E are the back forks, of which the back fork E on one side is composed of two parts 15 F G, the part F extending from the back-fork end D and the part G from the crank-bracket B, the part G being nearer the central plane of the frame than the part F.
- I is a stay-piece extending from the point 20 of connection K of the back stays C C and the center stay A to the point of division of the parts F G.

I have shown the design embodied in an ordinary diamond frame, but the particular character of the main portions of the frame 25 is not material to the design, the essential feature of which is the divided back fork E with the part I extending from the point of division of the parts F G to the point of union K of the center stay A and back stays C C. 30

Having now described my invention, what I claim as new, and desire to secure by Letters Patent, is—

The design for a bicycle-frame substantially as herein shown and described. 35

In testimony of which invention I hereunto set my hand.

THOMAS H. CARROLL.
